DESIGN.

—o—

O. HEINIGKE.

CARPET.

No. 17,645.

Patented Aug. 23, 1887.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 17,645, dated August 23, 1887.

Application filed July 21, 1887. Serial No. 244,941. Term of patent 3½ years.

To all whom it may concern:

Be it known that I, OTTO HEINIGKE, of New Utrecht, Long Island, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is made up of several larger cup-shaped or rose-like flowers, each resting on a

cluster or group of loosely-hanging leaves; also, of smaller star-shaped flowers surrounded with leaves or supported alone on a stem. These flowers and leaves are connected by 20 stems which are encircled or covered with a vine-like work. This vine-work also occurs here and there in the spaces between the larger figures.

What I claim as new, and desire to secure 25 by Letters Patent, is—

The design for carpets, consisting of the design substantially as shown.

OTTO HEINIGKE.
